UNITED STATES PATENT OFFICE.

AMOS R. BLACK, OF NEAR LAMAR, COLORADO.

AMALGAMATOR.

SPECIFICATION forming part of Letters Patent No. 681,034, dated August 20, 1901.

Application filed April 6, 1900. Serial No. 11,720. (No model.)

To all whom it may concern:

Be it known that I, AMOS R. BLACK, a citizen of the United States, residing near Lamar, in the county of Prowers and State of Colorado, have invented certain new and useful Improvements in Amalgamators; and I do hereby declare the following to be a full, clear, and exact description of the invention, such as will enable others skilled in the art to which it appertains to make and use the same.

My invention relates to wet-process amalgamators.

The object of the invention is the provision of an amalgamator of either small or very large capacity which will be adapted to amalgamate fine, flake, flour, or float gold from the pulp, thereby preventing the great loss at present existing in the milling of gold-bearing ores.

20 The foregoing object is accomplished by the provision of a novel arrangement of amalgamating-plates, pulp-stirrers, and other devices whereby a number of different currents and counter-currents are sent up in the pulp, 25 which insures the contact with the mercury surfaces of all infinitesimal particles in suspension in the pulp.

20 The invention will be described in detail hereinafter and the novel features recited in 30 the appended claims.

In the accompanying drawings, Figure 1 is a transverse section of the complete machine, arrows indicating the manner in which the pulp rises and dives; Fig. 2, a horizontal section on line α of Fig. 1; and Fig. 3, a detail 35 view of a plate-hanger and a section of amalgamating-plate, with the parts separated to illustrate the manner of fastening.

The machine has a tub 1, in practice from 40 five to thirty feet in diameter and about a foot and one-half deep, which is supported on sills 2, to which it is secured, so as to be stationary. A few of the staves constituting 45 the sides of the tub are shown at 3. An amalgamated copper plate 4, circular in shape, extends around the inside of the tub and is secured to the side thereof. Within the tub are stationary concentric amalgamated copper plates 5, 6, and 7. The concentric plates 50 5 and 7 are directly secured to the bottom of the tub, so that none of the pulp can pass underneath them, but must necessarily pass

over the upper edges. On the other hand, the plate 6 has its lower edge raised somewhat from the bottom of the tub to leave the 55 space 8 for the pulp to pass through, and said plate is secured to the tub-bottom by the legs 9. The plate 5 is of less height than the plate 4, so that the pulp will flow over the top of said plate 5 before it overflows the 60 plate 4. The plate 6 is of greater height than the plate 5 to prevent the pulp from flowing over the top of said plate 6 and to insure the passage of the pulp downward and under the plate. The plate 7 is of less height than the 65 other plates to insure the discharge of the pulp into the central discharge-chamber 10, formed by the said plate. The tub-bottom is provided with discharge-pipes 11, which carry off the pulp, and drain-plugs 12 are 70 provided for the amalgamating-chambers, by which said chambers can be drained when desired.

Arising from the tub-bottom in the overflow or discharge chamber is a standard 13, 75 carrying a bearing 14. There are arms 15, having a casting 16, which rests on the bearing 14 and to which it is connected by the set-screws 17 to a vertical shaft 18, mounted in a suitable bearing on the tub-bottom and 80 geared to a power-shaft 19, equipped with a belt-pulley 20, to which either animal or mechanical power can be applied to rotate the moving parts of the machine at a speed of about four or five revolutions per minute in 85 practice.

The arms 15 carry a feed-box 21 at their center, from which extend feed-pipes 22, which rest on the top of the arms and are secured thereto by clamps 23, while the ends 90 of the pipes project down into the outer amalgamating-chamber between the plates 4 and 5, as at 24, and are provided with lateral perforations 25 and a single perforation 26 in their lower ends.

Secured to and depending from the rotating arms 15 are plate-hangers 27, which are adapted to move in the two innermost amalgamating-chambers. The lower ends of these hangers have one half 28 made removable and secured to the other half by a bolt 29. The respective annular rotating amalgamating-plates 30 and 31, constructed in four sections each and removable, are hung

from the bolts 29 and clamped to the hangers by the parts 28. The top of said amalgamated plate 30 is lower than the top of plates 5 and 6, respectively, so as to allow the pulp 5 to pass over it and downward along both sides of said plate 30. The top of amalgamated plate 31 is lower than the top of the plate 7 in order to allow that portion of the pulp arising on the outside of plate 31 to flow over the top of said plate and discharge 10 to the central discharge-chamber.

The operation is as follows: The plates are prepared for amalgamating gold. Either animal or mechanical power is applied to the belt- 15 pulley to rotate the perforated feed-pipes. Prior to introduction in the amalgamator the material is reduced to at least eighty or one hundred mesh fine by the wet process and fed into the feed-box and through the rotating 20 feed-pipes by hydraulic pressure and is jetted out under the surface of the pulp in the amalgamating-chamber and through the perforations in the pipes as the latter rotate, thereby producing a lateral counter-current 25 and directing the pulp laterally against the concentric amalgamated plates. The hydraulic pressure from the feed-pipes causes the pulp to rise in the front chamber and pass over the second plate, then to dive in 30 the second chamber along both sides of the rotating plate and under the third stationary plate, and thence to pass up in the third chamber on both sides of the second rotating plate and over the second rotating plate, and 35 finally pass over the inner plate and discharge into the overflow-chamber and pass out therefrom through the drain-pipe, thereby producing upward and downward currents in the amalgamating-chambers. Another current is induced in the pulp—that is to say, a 40 circular current moving around the plates, produced by the rotation of the feed-pipes and the plate-hangers. Still another swirling current is set up in the pulp by the movement of the pulp as it falls in behind the 45 feed-pipes and the plate-hangers as they rotate to occupy the space from which the pulp is being continuously displaced. It will be seen, therefore, that four independent and 50 distinct different counter-currents are set up in the outer pulp-chamber and three distinct different counter-currents in the other two chambers, which make it impossible for any particle in the pulp (no matter how fine) to pass 55 through the machine without being brought in contact with a mercury-surface, and consequently all fine, flake, flour, or float gold will be amalgamated. The material—that is to say, the ore—is first reduced to eighty or one 60 hundred mesh fine by the wet process, preferably by an arrastre or scouring-mill which I have invented and which forms the subject of a separate application for patent. Ore that is reduced to this degree of fineness 65 loses its grit, and consequently by using only such reduced ore in the amalgamator there is no danger of scouring the mercury or

amalgam from the plates, because the different counter-currents produced are very gentle. The continuous rotation of the feed-pipes 70 and amalgamated-plate hangers acting as pulp-stirrers in the pulp-chambers and the upward and downward hydraulic current therein make it impossible for the material being treated to clog the amalgamator. The amalgamator can also be successfully used to save the fine float-gold now lost in the placer-mine dump by first screening off all material too "coarse" to be passed through the amalgamator. 75

Having thus described my invention, what I claim as new, and desire to secure by Letters Patent, is—

1. In a wet-process amalgamator, the combination with a tub, of amalgamated plates 85 therein, and perforated feed-pipes located between the plates and adapted to move between them which are adapted to feed material to be amalgamated to the plates in hydraulic jets under the surface of the pulp in 90 which said pipes move.

2. In a wet-process amalgamator, the combination with a stationary tub, and vertical concentric stationary amalgamator-plates 95 therein, of feed-pipes adapted to rotate between said plates, said pipes having perforations, whereby the material to be amalgamated is fed to the plates in hydraulic jets under the surface of the pulp in which the said pipes move. 100

3. In a wet-process amalgamator, the combination with a tub, of separated vertical stationary amalgamated plates in said tub, and a perforated feed-pipe movable between the amalgamated plates in the tub, whereby the 105 material to be amalgamated is fed to the plates in hydraulic jets under the surface of the pulp in which the feed-pipe moves.

4. In a wet-process amalgamator, the combination with a tub and separated stationary 110 amalgamated plates therein, of amalgamated plates located between the stationary plates and adapted to rotate between and in relation to them, a perforated feed-pipe movable between the stationary plates in the pulp 115 in the tub, whereby the material to be amalgamated is fed to the plates under the surface of the pulp in which the feed-pipe moves.

5. In a wet-process amalgamator, the combination with a stationary tub and circular 120 vertical stationary concentric amalgamated plates therein, of perforated pipes rotating between the plates, adapted to feed the pulp in hydraulic jets under the pulp-surface in the pulp-chamber. 125

6. In a wet-process amalgamator, the combination with a pulp-chamber, having a central discharge, and amalgamated plates in the pulp-chamber, which are arranged and adapted for over and under flow of the pulp 130 to produce a current thereover, of means for feeding the pulp to the plates, and means for introducing fluid-jets in the pulp between the plates and toward them.

7. In a wet-process amalgamator, the combination with a pulp-chamber and amalgamated plates therein, of means for feeding pulp to the plates, means for producing distinct and independent or different currents in the pulp along or against the amalgamated plates, and means for directing fluid-jets in the pulp toward the said plates whereby fine gold is made to contact with the amalgamated plates.

8. In a wet-process amalgamator, the combination with a pulp-chamber and amalgamated plates therein, of a feeder adapted to deliver the pulp below the liquid-surface in

15 the space between the plates and in jets directed toward said plates, said plates and feeder being relatively movable whereby an independent and distinct current is produced in the pulp against said plates.

20 9. In a wet-process amalgamator, the combination with a pulp-chamber and amalg-

mated plates therein, of a conduit intermediate the plates adapted to project currents against the plates, below the surface of the pulp, said plates and conduit being relatively 25 movable, and said conduit also creating by its movement distinct and independent currents in the pulp.

10. In a wet-process amalgamator, the combination of a pulp-chamber and amalgamated plates therein, and fluid-conduits intermediate the plates adapted to project fluid-currents against the plates, below the surface of the pulp, said plates and conduits being relatively 30 movable.

35 In testimony whereof I affix my signature in presence of two witnesses.
